CLAIM

The ornamental design for an earring storage and display stand, as shown and described.

DESCRIPTION

FIG. 1 is a perspective view of an earring storage and display stand showing our new design;
FIG. 2 is a left side elevational view, the right side being a mirror image thereof;

FIG. 3 is a rear elevational view thereof; and
FIG. 4 is a fragmentary cross sectional view thereof,
taken on line 4—4 of FIG. 3.

FIG. 1

FIG. 4

FIG. 2

FIG. 3
